UNITED STATES PATENT OFFICE.

HYMAN MARGOLIN, OF NEW YORK, N. Y.

DESIGN FOR A HAND BAG.

Application filed June 30, 1926. Serial No. 18,217. Term of patent 3½ years.

To all whom it may concern:

Be it known that I, HYMAN MARGOLIN, a citizen of the United States, and a resident of the city of New York, borough of Manhattan, in the county and State of New York, have invented a new, original, and ornamental Design for Hand Bag, of which the following is a specification, reference being had to the accompanying drawing, forming part thereof.

The figure is a perspective view of a hand bag, showing my new design.

I claim:

The ornamental design for a hand bag, as shown.

HYMAN MARGOLIN.
